FIG. 5.

INVENTOR
ALBERT NEAL

BY
Albert Neal

ATTORNEY

Patented Sept. 2, 1924.

UNITED STATES PATENT OFFICE.

ALBERT NEAL, OF KOKOMO, INDIANA.

WRENCH.

Application filed September 13, 1922. Serial No. 588,007.

To all whom it may concern:

Be it known that I, ALBERT NEAL, a citizen of the United States, residing at Kokomo, in the county of Howard and State of Indiana, have invented certain new and useful Improvements in Wrenches, of which the following is a specification.

This invention relates to wrenches and particularly to that class adapted to be used for tightening or loosening nuts, bolts and the like, and one feature of the invention is the provision of a fixed jaw and a movable jaw with means associated with the handle of the wrench for operating the movable jaw to position it towards or from the fixed jaw.

A further feature of the invention is in so constructing the fixed jaw and parts of the handle structure that the openings in the fixed jaw will form a pivot bearing for exerting tensions on the handle section.

A further feature of the invention is the provision of a crank pin adapted to co-operate with a slot in the movable jaw whereby when the handle is swung in the arc of a circle on its pivot the movable jaw will be shifted towards or from the fixed jaw.

A further feature of the invention is the provision of a handle formed in sections and means for connecting the sections together so that the handle portion may be readily attached to or removed from engagement with the fixed jaw.

Other objects and advantages will be hereinafter more fully set forth and pointed out in the accompanying specification.

In the accompanying drawings,

Figure 1 is a perspective view of the wrench ready to be applied to use,

Figure 2 is a side elevation thereof showing the movable jaw positioned adjacent the fixed jaw as when engaging an object,

Figure 3 is an elevation of the jaw portions of the wrench with the handle portion removed,

Figure 4 is a sectional view as seen on line 4-4, Figure 1.

Figure 5 is a detail edge elevation of the handle structure, and

Figure 6 is a perspective view of the movable jaw.

Referring to the drawings, 1 and 2 indicate respectively the fixed and movable jaws of the wrench, the movable jaw 2 having a shank 3 which extends at right angles to the trend of the movable jaw 2 and is entered in a slot 4 extending from edge to edge through

the fixed jaw 1, the slot being so arranged that the movable jaw may slide towards or from the fixed jaw.

The movable jaw 2 is adjusted back and forth for engaging the movable and fixed jaws with an object through the medium of a handle 5 which is preferably formed of two companion sections, the upper ends of which are separated for passing on opposite sides of the fixed jaw 1, said separated ends terminating in circular heads 6 which enter and fit in bores 7 transversely through the fixed jaw 1, said heads forming a bearing or fulcrum in said bores for the handle, the inner faces of the heads terminating substantially flush with the side faces of the shank portion of the movable jaw.

Extending transversely through the heads 6 and eccentrically of the axes thereof is a crack pin 8 which passes through an opening 9 in the shank 3, said opening 9 preferably extending at an angle to the vertical plane of the shank so that when the handle 5 is swung to the right or left the heads 6 and crack pin 8 will act as an eccentric on the movable jaw through the inclination of the opening 9 and move said jaw towards or from the fixed jaw. The two sections of the handle are secured together by one or more screws or rivets 10 which pass transversely through the two sections of the handle and by forming the handle in this manner it can be readily assembled with the fixed jaw by first placing the two sections of the handle on opposite faces of the fixed jaw and entering the head portions 6 thereof in the bores 7, and when the two portions of the handle are brought together they are secured together by the screws or rivets. The shank portion of the movable jaw is then entered in the slot 4 and moved inwardly until the opening 9 comes in registration with the opening through the heads 6 for the reception of the crank pin 8 after which the crank pin is secured in the heads and through the opening 9. The two sections of the handle are then secured together when the wrench is ready for use.

In applying the wrench to use the handle 5 is positioned as shown in Figure 1 and the jaws entered on opposite sides of the object to be turned. The handle 5 is then swung laterally as shown in Figure 2 of the drawings until the jaws are securely clamped against the object to be turned when by continued pressure against the han-

dle 5 the object will be rotated. For reverse rotation of the object the position of the wrench is reversed so that the pull against the handle will be in the opposite direction. The swinging movement of said handle 5 is limited by shoulders 11 and 12.

By providing the heads 6 so that they will enter the bores 7 of the fixed jaw a perfect fulcrum will be provided and the strain 10 on the parts of the wrench reduced to a minimum owing to the diameter of the heads and the manner of operating the movable jaw through the medium of the crank pin.

15 It will likewise be seen that in view of the simplicity of the device it can be very cheaply manufactured and readily assembled, and when applied to use will be positive and effective in its operation.

20 Having thus fully described my said invention, what I claim as new and desire to secure by Letters Patent, is:

1. In a wrench, a fixed jaw having circular bores extending from side to side thereof, and a slot extending from edge to edge thereof and intersecting said bores, a movable jaw having a shank entering said slot and housed therein, said shank having an opening therethrough, a handle having cir-

cular heads at one end bifurcated to fit on 30 opposite sides of said shank and within said bores, said heads pivoting the handle to the stationary jaw, and a crank pin connected with said heads and extending through said opening in the shank for operating the movable jaw when the handle is 35 swung laterally.

2. A wrench comprising a fixed jaw having a slot extending from edge to edge thereof and a transverse bore intersecting 40 said slot, a movable jaw having a shank entering said slot, said movable jaw having an inclined opening therethrough, a two-part handle having circular heads at one 45 end adapted to enter the bores of the fixed jaw, a crank pin carried by said heads extending through the opening in the shank of the movable jaw, and means for securing the parts of the handle together.

In witness whereof, I have hereunto set 50 my hand and seal at Indianapolis, Indiana, this 11th day of September, A. D. nineteen hundred and twenty-two.

ALBERT NEAL. [L. S.]

Witnesses:

M. L. SHULER,
MARGARET E. GAMBLYN.
